Attorney.

UNITED STATES PATENT OFFICE.

CARL C. MULDNER, JR., OF MAPLEWOOD, MISSOURI.

TOY.

1,238,554.

Specification of Letters Patent. Patented Aug. 28, 1917.

Application filed April 21, 1916. Serial No. 92,799.

To all whom it may concern:

Be it known that I, CARL C. MULDNER, Jr., a citizen of the United States, residing at Maplewood, in the county of St. Louis and 5 State of Missouri, have invented certain new and useful Improvements in Toys, of which the following is a specification.

My invention relates to toys, and more particularly to that class of mechanical toys 10 known as turbines or engines adapted to be propelled by means of either hot or cold-air currents or drafts.

The object of my invention is to provide a simple, cheap and durable toy turbine or 15 engine adapted to be propelled by means of the hot-air currents escaping into a room from a hot-air register or from cold-air drafts blowing through a window, door, or similar opening.

20 With the above and other objects in view, the invention consists in certain new and novel arrangements and combination of parts, as will be more fully described hereinafter and finally pointed out in the claims 25 hereto appended.

Referring to the accompanying drawings forming a part of this specification wherein like characters of reference denote similar parts throughout the several views:

30 Figure 1 is a front elevation of a toy constructed in accordance with my invention. Fig. 2 is a sectional view thereof.

In carrying out the aim of my invention I employ a preferably flat, metallic sheet 1 35 constituting the base of my toy. The base is provided with a central opening 2 to permit air currents to pass through the base. Each corner of the base is preferably bent at a right angle to the base, as at 3. The 40 bent corners 3 are adapted to be inserted into crevices or openings in the hot-air register (not shown) for normally supporting the base in position upon a hot-air register.

A preferably circular band 4 is arranged 45 concentrically with the opening 2 in the base 1. This band is mounted upon the base 1 and suitably secured thereto by means of solder, or any other suitable fastening means, as at 5. This arrangement it will be 50 observed provides an air passage through the band communicating with the opening in the base 1.

A fan-wheel 6 consisting of a plurality of radially disposed twisted blades is arranged 55 concentrically with the opening 2 and the passage formed by the metallic band, and

is mounted to revolve within the passage formed by the band 4.

The fan-wheel 6 is formed from a single sheet of metal preferably from the circular 60 piece stamped from the base 1 for providing the opening 2. The fan-wheel 6 is suitably secured to a drive shaft 7. Drive-shaft 7 is suitably and rotatably supported at each end by means of a pair of opposed cross-pieces 8 constituting bearings. These cross-pieces or bearings 8 span the passage formed by the band 4 and are bent at each end and secured to the inner wall of the band 4 by solder, or by any other suitable fastening 65 means, as at 9, for holding the cross-pieces in position. A brass or other suitable washer or bushing 10 is suitably secured to the cross-pieces 8 through which the drive-shaft 7 is adapted to pass. These washers 70 or bushings provide a more substantial bearing for the drive-shaft 7 than the mere thickness of the metal of the cross-pieces 8.

The blades of the fan-wheel 6 are bent substantially at an angle of forty-five degrees, although they may be bent to any other suitable angle desired or found best adapted for the purpose intended. The blades may be curved if found desirable.

A suitable pulley 11 is secured to the outer 85 end of the drive-shaft 7. A suitable belt 12 may be driven by means of the pulley for propelling other toys, if desired. This toy, in such instance, then acting as the source of power.

90 From the foregoing description it will be observed that I provide a toy adapted to act as an engine or turbine thereby taking the place of the usual toy steam engine and eliminating the use of water and fuel as used 95 in toy steam engines, hence making my device a safer and more economical toy for the amusement of children.

It will be remembered that my toy can be actuated by either hot or cold-air currents, 100 that the hot-air currents are utilized preferably from the hot-air registers in a home, and the cold-air currents that may pass through a window, a door, or similar opening.

What I claim is:

1. A toy comprising a supporting plate having a central opening, a circular band of a diameter approximately the same as said central opening secured to the top of said plate and arranged concentrically with the 110 opening in said plate to form an air-passage, a cross-piece secured at each end to

opposite sides of said band at the upper edge thereof so that the upper face of said cross-piece will lie flush with the upper edge of said band, a second cross-piece spanning the 5 air-passage formed by said circular band, said second cross-piece being positioned directly below said first-mentioned cross-piece and having its ends secured to the inner face of the band a suitable distance above 10 the lower edge of said circular band, a drive-shaft revolubly mounted in and supported by said upper and lower cross-pieces, a one-piece fan wheel formed by radially slitting a circular blank and providing a plurality 15 of fan blades adapted to be twisted to permit the fan wheel being rotatably driven by means of air-currents passing through the aforesaid air passage, and a drive-pulley fixed to the end of the drive-shaft adjacent 20 cent the upper cross-piece.

2. A toy comprising a supporting plate having a central opening of considerably less diameter than the width of said plate, a circular band positioned at its lower end in 25 said opening and fixed at its lower end to said plate, said circular band being of a sufficient height to provide an air-passage, said plate being greater in diameter than said circular band to retard air-currents 30 passing around the edge plate and periph-

ery of the circular band, a supporting finger formed at each corner of said plate by bending each corner downwardly, said fingers adapted to be inserted into the openings of a hot-air register grate when said grate is 35 located in the vertical wall of a room for retaining the toy in position upon the grate, a cross-piece secured at each end to opposite sides of said band at the upper edge thereof so that the upper face of said cross-piece 40 will lie flush with the upper end of said band, a second cross-piece spanning the air-passage formed by said circular band, said second cross-piece being positioned directly 45 below said first-mentioned cross-piece and having its ends secured to the inner face of the band a suitable distance above the lower edge of said circular band, a drive shaft revolubly mounted in and supported by said upper and lower cross-pieces, a one-piece 50 fan wheel formed by radially slitting a circular blank and providing a plurality of fan blades adapted to be twisted to permit the fan wheel being rotatably driven by means of air-currents passing through the aforesaid air-passage, and a drive pulley fixed to the end of the drive shaft adjacent the 55 upper cross-piece.

CARL C. MULDNER, JR.
